US0D1006394S

(12) **United States Design Patent** (10) **Patent No.:** **US D1,006,394 S**
(45) **Date of Patent:** **** Nov. 28, 2023**

(54) **NESTED NESTABLE DRUMS**

(71) Applicant: **GEO Plastics**, Los Angeles, CA (US)

(72) Inventors: **Michael Abraham Morris**, Rancho Palos Verdes, CA (US); **William Michael Palleva**, Cerritos, CA (US)

(73) Assignee: **GEO Plastics**, Los Angeles, CA (US)

(**) Term: **15 Years**

(21) Appl. No.: **29/790,628**

(22) Filed: **Dec. 6, 2021**

Related U.S. Application Data

(62) Division of application No. 29/719,545, filed on Jan. 6, 2020, now Pat. No. Des. 938,128.

(57) **CLAIM**

The ornamental design for nested nestable drums, as shown and described.

DESCRIPTION

FIG. 1 is a left, front, and top perspective view of nested nestable drums;

FIG. 2 is a right, back, and bottom perspective view of the nested nestable drums of FIG. 1;

FIG. 3 is a back elevational view of the nested nestable drums of FIG. 1;

FIG. 4 is a front elevational view of the nested nestable drums of FIG. 1;

FIG. 5 is a left elevational view of the nested nestable drums of FIG. 1;

FIG. 6 is a right elevational view of the nested nestable drums of FIG. 1;

FIG. 7 is a top plan view of the nested nestable drums of FIG. 1; and,

FIG. 8 is a bottom plan view of the nested nestable drums of FIG. 1.
